UNITED STATES PATENT OFFICE.

WESLEY M. ROSE, OF SACRAMENTO, CALIFORNIA.

SANITARY DRINKING-FOUNTAIN.

1,111,325.

Specification of Letters Patent.

Patented Sept. 22, 1914.

Application filed June 11, 1913. Serial No. 773,000.

To all whom it may concern:

Be it known that I, WESLEY M. ROSE, a citizen of the United States, residing at Sacramento, in the county of Sacramento and 5 State of California, have invented new and useful Improvements in Sanitary Drinking-Fountains, of which the following is a specification.

This invention relates to a drinking fountain, and particularly pertains to a sanitary drinking fountain for public use.

It is the object of this invention to provide a drinking fountain in which the discharge nozzle and the stream ejected therefrom can not come in contact with the lips of the person obtaining a drink, thereby preventing contamination of the fountain and rendering it proof against the spread of infectious and contagious diseases.

20 A further object is to provide a drinking fountain which is so constructed as to render it impossible for a person to obtain a drink by placing the mouth to the fountain, and which will necessitate the use of an individual drinking tube or straw in order to obtain the liquid from the fountain.

Another object is to provide a drinking fountain of the above character which is simple in construction and economical in 30 manufacture.

The invention primarily resides in a fountain head formed with a vertically-disposed drinking tube connected with a source of liquid supply and having an overflow opening in its walls some distance below its upper end, a casing inclosing the drinking tube provided with a drain outlet, and means for preventing the liquid from being drawn from the open upper end of the drinking tube by suction applied to the end of the tube.

The invention further consists of the parts and the construction and combination of parts as hereinafter more fully described and claimed, having reference to the accompanying drawings, in which—

Figure 1 is a view in elevation of the invention. Fig. 2 is a plan view of same, with portions broken away. Fig. 3 is a detail vertical section on the line $a-a$ of Fig. 2. Fig. 4 is a horizontal section on the line $b-b$ of Fig. 1. Fig. 5 is a vertical section of a modified form of the invention.

In the drawings A represents a feed pipe 55 leading from any suitable source of liquid

supply, on the end of which a regulating valve 2 is mounted. Connecting with the discharge opening of the valve 2 is a fountain head which embodies the present invention. This fountain head comprises a horizontal basin 4, formed with a nipple 5, adapted to be screwed into the discharge opening of the valve 2; the nipple 5 having an opening 6 therein communicating with the discharge opening of the valve 2 at one end, and opening in an enlarged end portion to the dished upper face of the basin 4. Extending upwardly from the basin 4 is a drinking nozzle 7, the lower end of which extends into the enlarged upper end of the opening 6 and forms a continuation thereof. The upper end of the nozzle 7 terminates in and is secured to a cap member 8 which may be constructed in one piece and formed integral with the nozzle 7, as shown in Fig. 5, or 75 may be composed of two pieces c and d , as shown in Figs. 2 and 3. In the latter instance, the member d forms a shield or covering for the upper end of the nozzle 7 to prevent the nozzle being contacted by the 80 lips of the person obtaining a drink therefrom; the cap d being spaced a short distance above the upper termination of the nozzle 7 and formed with an opening e at a point directly above the open upper end of 85 the nozzle 7.

Mounted on the basin 4 and surrounding the nozzle 7 is a transparent tube 9, which tube is spaced a short distance from the nozzle 7 and is held in place by means of the 90 cap 8. Gaskets or packing rings 10 are interposed between the ends of the tube 9 and the cap 8 to form tight joints.

In the form of the invention shown in Figs. 1, 2, 3 and 4, the cap 8 is held in place 95 by means of screws 11 which pass through the lower member c of the cap 8 and are threaded into the basin 4, as particularly shown in Fig. 3; the screws 11 and the member c of the cap 8 being put in place 100 before the member d is applied. The member d is soldered or otherwise fastened to the member c after the member c has been secured in place by the screws 11. In this form of the invention the transparent tube 105 9 will be clamped on the basin 4 by means of the screws 11. In the form of the invention shown in Fig. 5 the nozzle 7 is formed integral with the cap 8, and is threaded at its lower end so as to screw into the basin 4; 110

the transparent tube or casing 9 being clamped in place between the basin 4 and the cap 8.

An important feature of this invention resides in forming the nozzle 7 with an opening 12 of comparatively large area a short distance above the bottom of the basin 4. This opening 12 may be formed by dividing the nozzle 7 into two pieces and separating them to form a space, as shown in Figs. 1 and 3; or the opening 12 may comprise a series of perforations, as shown in Fig. 5. The purpose of this opening, or openings 12, is to prevent the liquid delivered to the nozzle 15 from being discharged at its open upper end; the valve 2 being constructed to permit the flow of only such quantity of liquid into the nozzle 7 as will rise a short distance above the openings 12. By this construction 20 the liquid will be discharged from the nozzle 7 through the openings 12, into the basin 4, from whence it is discharged through a drain outlet 13, into any suitable conduit, not shown. Means are provided for preventing 25 the liquid delivered to the nozzle 7 from being drawn from its upper end by suction applied directly to the nozzle. In the form of the invention shown in Figs. 1, 2 and 3, this means consists of a series of perforations *f* in the member *d* and a perforation *g* in the member *c*. These perforations *f* and *g* serve to break a suction applied to the upper end of the nozzle 7 by permitting the passage of air therethrough, thus preventing a 35 person from obtaining a drink from the fountain by placing the mouth over the nozzle 7 or cap 8.

In the form of the invention shown in Fig. 5, perforations *h* are formed in the nozzle 7 immediately below the cap 8, which perforations serve the same function as the perforations *f* and *g* in the form of the device shown in Fig. 3.

It is essential to so construct the fountain 45 head that the cap 8 cannot be readily removed. This is accomplished in the form of the invention shown in Figs. 1 to 4, inclusive, by inclosing the screws 11 beneath the cap member *d*, and in the form shown in Fig. 5 by engaging the threaded portion of the nozzle 7 with pins 14 inserted through the nipple portion 5 of the basin 4. The pins 14 may cross the opening 6, as shown in Figs. 3, 4 and 5, so as to form barriers for 55 breaking up the stream discharged through the nozzle 7.

When it is desired to obtain a drink from the fountain the valve 2 is opened and a drinking tube or straw is introduced into 60 the open upper end of the nozzle 7, and inserted into the body of the liquid adjacent to the opening 12, as indicated at *i* in dotted lines in Fig. 3; the person using the fountain obtaining a drink through the use of 65 individual straws or tubes which may be

discarded after being once used. By this construction contamination or fouling of the fountain is absolutely prevented.

It will be seen that the upper portion of the nozzle 7 serves as a means for preventing the drinking tube being introduced into the liquid in the basin 4, and that the casing comprising the members 8 and 9 prevents the nozzle being handled at the point of overflow.

It is manifest that the form and details of construction of the invention are subject to modifications without departing from the principles thereof, and the right is reserved to make such changes and alterations as will 80 come within the scope of the appended claims.

Having thus described my invention, what I claim and desire to secure by Letters Patent, is:

1. In a sanitary drinking fountain, a basin having a drain outlet, a tubular member having an open upper end connected to the basin, a water inlet which communicates with the lower end of the tubular member, said member having an overflow outlet located between its ends and at a point slightly above the basin bottom, a closure for the basin which is located adjacent to the upper end of the tubular member, said closure acting as a guard for the member and having an opening which registers with the tubular member and which allows of the insertion of a drinking tube therethrough so that the tube may be projected into the tubular member below the overflow outlet of the latter, and a valve controlling the water inlet and formed to permit only such quantity of water to enter the tubular member as will rise a short distance above the overflow outlet.

2. In a sanitary drinking fountain, a basin having a drain outlet, a hollow transparent member seating on the basin, a cap secured to the upper end of said member, a water supplying tube secured to the cap and basin and having overflow outlets arranged above the basin and in close proximity to the latter, the upper end of the tube being open, a member secured to the cap and overlying the open upper end of the tube in spaced relation thereto and having an opening which registers with the tube, and a valve controlling the supply of water to said tube and formed to permit only such quantity of water to enter the tube as will rise a short distance above the overflow outlets.

3. In a sanitary drinking fountain, a basin having a drain outlet, a tubular member having an open upper end connected to the basin, a water inlet which communicates with the lower end of the tubular member, said member having an overflow outlet located between its ends and at a point slightly above the basin bottom, a closure for the

- basin which is located adjacent to the upper end of the tubular member, said closure acting as a guard for the member and having an opening which registers with the tubular member and which allows of the insertion of a drinking tube therethrough so that the tube may be projected into the tubular member below the overflow outlet of the latter, there being an air inlet for the tubular member located below the closure to prevent liquid from being drawn from the open upper end of the member by suction applied to said member end, and a valve controlling the water inlet and formed to permit only such quantity of water to enter the tubular member as will rise a short distance above the overflow outlet.
4. In a sanitary drinking fountain, a basin having a drain outlet, a hollow transparent member seating on the basin, a cap secured to the upper end of said member, a water

- 20

supplying tube secured to the cap and basin and having overflow outlets arranged above the basin bottom and in close proximity thereto, the upper end of the tube being open, there being air inlets for the tube located adjacent to the cap to prevent liquid from being drawn from the open upper end of the tube by suction applied to said tube, and a valve controlling the supply of water to said tube and formed to permit only such quantity of water to enter the tube as will rise a short distance above the overflow outlets. 25
